DENOYER-GEPPERT COMPANY, OF CHICAGO, ILLINOIS

SUPPORT FOR MAPS AND ANALOGOUS DEVICES

Application filed January 3, 1928. Serial No. 244,349.

The invention aims to provide a new and improved device for advantageously supporting a map, a picture-carrying sheet, a curtain or the like upon a wall, for instance, the wall 5 of a schoolroom.

The device embodies a track secured to the wall and having upper and lower parallel edges spaced from said wall, and a plurality of slides to engage the track for supporting 10 the map, picture-carrying sheet or the like. It is one object of the invention to provide novel co-operable construction of track and slides, permitting quick and easy engagement of said slides with the track or disengagement 15 therefrom with equal facility.

The track is formed of sections and it is a further object to provide unique connecting means between said sections which serve also to space the track outwardly from the wall. 20 A still further object is to provide novel and advantageous construction for the slides.

With the foregoing in view, the invention resides in the novel subject matter hereinafter described and claimed, description being accomplished by reference to the accompanying drawings.

Fig. 1 is a fragmentary elevation showing the invention in use.

Fig. 2 is a top plan view of the parts shown 30 in Fig. 1.

Fig. 3 is an enlarged horizontal sectional view through one of the track joints as indicated by line 3—3 of Fig. 1.

Fig. 4 is an enlarged elevation of one of 35 the slides and the adjacent portion of the track.

Fig. 5 is a vertical sectional view on line 5—5 of Fig. 4.

Figs. 6 and 7 are respectively, a front elevation and an edge view of a metal-bound block of cork or other yieldable material embodied in the slide construction and adapted to be readily penetrated by thumb tacks.

Fig. 8 is an elevation of the metal blank 45 which holds the block of cork or the like and forms therewith one of the track-engaging slides.

Fig. 9 is a view similar to Fig. 1 but illustrating the slides which are used when a roller map is to be supported.

Fig. 10 is a side elevation of one of the slides shown in Fig. 9.

In the drawings above briefly described, 11 denotes a horizontal track formed of elongated sections 12, each in the form of a single 55 metal strap. The ends of the sections 12 abut each other and overlap a relatively narrow splice plate 13 which serves to space the track sections 12 outwardly from a wall or other support by which they are carried, as well 60 as functioning as part of a joint between said sections. Splice plate 13 is formed with screw holes 14 and the sections 12 have countersunk openings 15 to receive screw heads. Thus, when fastening screws 16 are passed 65 through the aligned openings 14—15 and threaded into the wall or the like 17, these screws attach the track structure to the wall or other support and at the same time complete connection of the track sections with 70 each other.

The lower edge of each track section 12 is formed with one or more notches such as 18, which notches are instrumental in the attachment and detachment of slides herein- 75 after described.

In the present showing, we have disclosed two different types of slides S and S' respectively. Each slide S is formed from a metal plate 19 of the form shown in Fig. 8, and a block of cork or other material 20 (Figs. 6 and 7), this block being preferably bound by a strip of sheet metal 21, extending around its edges. The plate 19 lies against the rear face of the block 20 and its upper and lower ends 22—23 respectively are bent forwardly and then vertically, so that they clinch around the upper and lower portions of the block 20 and secure it to the plate. The body portion of this plate is provided with two rearwardly bent lugs 24 of angular form, to slidably engage the upper and lower edge portions of the track 11 as seen most clearly in Fig. 5. When the lowermost of the lugs or hooks 24 is opposite one of the notches 18, the entire slide S may be moved forwardly at its lower portion and hence the upper lug or hook may be lifted from the track, permitting quick and easy disengagement of the entire slide from said track. Similarly, when a slide is to be 100

engaged with the track, this may be easily done at a notched portion of said track, by passing the upper hook or lug 24 over the upper edge portion of the track and then 5 righting the slide so its lower hook or lug 24 will pass through the notch 18.

Preferably the upper end of the plate 19 is provided with an integral tongue 25 which 10 extends forwardly and then upwardly from the slide to provide a hook. These hooks of a number of the slides are often instrumental in supporting maps having rings, grommets or the like at their upper ends. The blocks 20 of cork or other suitable material, may 15 readily receive thumb tacks, for attaching pictures or other articles in sheet form, to the slides S to be suspended by the latter.

The slides S' shown in Figs. 9 and 10, are provided with upper and lower hooks or lugs 24 to engage the track 11 in the same manner as the hooks or lugs 24. These slides embody 20 forwardly projecting arms 26 for disposition at opposite ends of the roller 27 of a roller map 28. Each arm 26 is formed with a slot 25 and with a circular opening 30 shaped to fit the usual flat and round pintles at the 25 ends of the roller 27, it being understood that the flat pintle at one end of the roller will be received in the slot 29 of one of the arms 26 30 while the cylindrical pintle at the other end of said roller is then received in the circular opening 30 in the arm 26 of another slide. Like the slides S, the slides S' may be quickly 35 and easily attached and detached and slid into any desired spaced relation. To prevent disengagement of them from the roller 27 however, set screws 31 are preferably provided to contact with the track 11.

Attention is invited to the fact that each 40 bracket 26 is formed with a slot 29 and a circular opening 30. This readily adapts these brackets to supporting map rollers on which the map is rolled either face in or face out, the flat roller pintle being at one end of 45 the roller in one instance but at the other end thereof in the other instance. In many schools, there are sets of maps in racks arranged in such way that the maps roll face out, and in the same schools there are maps 50 used on spring roller boards and the like which roll the other way, that is face in, in the same manner as most spring roller curtains. The brackets herein disclosed permit the use of maps of either kind.

55 Excellent results are obtainable from the general construction shown and described and such construction is therefore preferably followed. However, within the scope of the invention as claimed, minor variations may 60 be made.

We claim:—

1. In a sheet suspending means, a block of 65 material into which thumb tacks may be forced, a plate disposed vertically and contacting with the rear side of said block, means

securing said plate and block together, and upper and lower hooks secured to and projecting rearwardly from said plate for engagement with an elevated track.

2. In a sheet suspending means, a block 70 into which thumb tacks may be forced, a metal plate disposed vertically and contacting with the rear side of said block, the upper and lower ends of said plate being bent forwardly and clinched around the upper and lower portions of said block to secure plate and block together, and upper and lower hooks secured to and projecting rearwardly from said plate for engagement with an elevated track.

3. In a sheet suspending means, a block 75 into which thumb tacks may be forced, a metal plate disposed vertically and contacting with the rear side of said block, the upper and lower ends of said plate being bent forwardly and clinched around the upper and lower portions of said block to secure plate and block together, and upper and lower hooks stamped rearwardly from said plate to engage upper and lower edges of an elevated 80 track.

In testimony whereof we have hereunto affixed our signatures.

ROY M. MEYER.
LEVINUS P. DENOYER.
